M. O'LEARY.
FLOOR CONNECTION FOR CLOSET BOWLS AND SOIL PIPES.
APPLICATION FILED SEPT. 11, 1915.

1,206,580.

Patented Nov. 28, 1916.

UNITED STATES PATENT OFFICE.

MICHAEL O'LEARY, OF SYRACUSE, NEW YORK.

FLOOR CONNECTION FOR CLOSET-BOWLS AND SOIL-PIPES.

1,206,580.

Specification of Letters Patent. Patented Nov. 28, 1916.

Application filed September 11, 1915. Serial No. 50,220.

To all whom it may concern:

Be it known that I, MICHAEL O'LEARY, a citizen of the United States of America, and resident of Syracuse, in the county of Onondaga, in the State of New York, have invented new and useful Improvements in Floor Connections for Closet-Bowls and Soil-Pipes, of which the following, taken in connection with the accompanying drawings, is a full, clear, and exact description.

This invention relates to an improved floor connection for a soil pipe and closet bowl involving the use of a suitable packing ring between the base of the bowl and pipe to prevent leakage at the joint.

The main object is to provide simple means whereby the packing ring may be conveniently adjusted from the exterior of the bowl after the latter has been firmly placed in operative position upon the floor in connection with the soil pipe.

Other objects and uses relating to specific parts of the device will be brought out in the following description.

In the drawings Figure 1 is a horizontal sectional view of the base of a closet bowl showing the means for clamping the bowl to the soil pipe and the additional means for adjusting the packing ring after the bowl has been properly placed or set up. Fig. 2 is a transverse vertical sectional view taken on line 2-2, Fig. 1. Fig. 3 is a perspective view of the detached collar which is attached to the upper end of the soil pipe, showing the threaded studs by which the base flange of the bowl is secured to the collar. Fig. 4 is a detail sectional view taken on line 4-4, Fig. 1, showing the manner of adjusting the packing ring from the exterior of the bowl. Fig. 5 is a perspective view of the detached packing ring. Fig. 6 is a sectional view similar to Fig. 2, showing the packing ring or follower in direct contact with the collar and soil pipe.

In order that my invention may be clearly understood, I have shown portions of a closet bowl —1— and soil pipe —2— as aligned with each other through an opening —a— in a floor —A— for direct communication one with the other, the bowl —1— being provided with the usual flanged base —3— of sufficient diameter to rest upon the floor around the opening —a— and also provided with a reduced annular flange —4— depending from the center thereof and coaxial with the soil pipe —2— to form a con-

tinuation of the opening therethrough into the bowl, the adjacent ends of the flange —4— and pipe —2— being both extended into the opening in the floor. A collar —5— is attached to the upper end of the pipe —2—, preferably by screw threads, so as to form a gas and liquid-tight joint and also to permit limited adjustment of the collar relatively to the floor to which it is secured by suitable fastening means as screws —6—.

As illustrated, the collar is circular and provided intermediate its lower and upper ends with a laterally projecting annular flange —7— resting upon the floor and provided at intervals with apertures for receiving the fastening screws —6—, the lower portion of the collar being inserted in the opening —a—.

The interior diameter of the upper part of the collar is somewhat larger than that of its lower end which is secured to the pipe —2— and is also of greater diameter than the exterior diameter of the flange —4— to form an annular chamber for the reception of an adjustable follower or packing ring —8—, said collar being provided with a conical face —9— between its ends to form a seat for the packing ring or follower —8— which is closely fitted upon the exterior or periphery of the flange —4— but so as to be movable axially thereon.

The base flange —3— of the closet is provided with a substantially flat horizontal portion —10— and a vertical portion —11— depending from the marginal edge thereof so as to rest upon the upper face of the floor —A—, thus forming with the inner flange —4— a chamber —12— of sufficient size to receive and conceal the collar —5— and packing ring —8— when the closet bowl is adjusted for use.

The flange —7— of the collar —5— is also substantially flat and horizontal and rests upon the upper surface of the floor within the upright portion —11— of the base flange —3— and is provided with a plurality of, in this instance four, vertically rising studs or bolts —13— cast therein or otherwise rigidly secured thereto to prevent turning, said bolts being passed loosely through apertures —14— in the horizontal portions —10— of the base flange —3— and are also passed loosely through and above apertured blocks —15— which rest upon the horizontal portions —10—, the upper ends of the bolts being threaded and engaged by nuts

—16—, whereby the base flange —3— is firmly clamped against the upper face of the floor —A—, and at the same time serves to secure the block —15— in fixed relation to the base flange and the base flange in fixed relation to the collar so that the soil pipe and bowl become firmly connected as a unit when the closet is adjusted for use.

The follower or packing ring —8— is provided with a series of, in this instance four, radially projecting bearings —8'— adapted to be engaged by a corresponding number of adjusting screws —17— which are secured in threaded apertures —18— in the blocks —15—.

Each of the bolt openings —14— is preferably of sufficient circumferential length to receive one of the bolts —13— and the adjacent adjusting screw —17— so that each of the blocks —15— which receives one of the bolts —13— and adjacent adjusting screw —17— overhangs the corresponding opening —14— and adjacent arm or bearing —8'— of the follower —8—, thus allowing the adjusting screws to extend some distance above the base flange —3— of the closet bowl where it is always accessible for manipulation by screw driver or other suitable implement for tightening the collar or packing ring when necessary without in any way disturbing any of the other connections or fastenings by which the bowl is connected to the floor and to the soil pipe.

In order that the bearings —8'— for the adjusting screw —17— may be positively and accurately registered with said adjusting screws, the collar —5— is provided with an upstanding flange —19— having a series of, in this instance four, recesses —20— of substantially the same width and in the same spaced relation as said arms or bearings to receive the same and allow limited axial adjustment of the follower by means of the adjusting screw —17— after the bowl is secured in place.

The follower is provided with an inner packing section —21— which might be the flanged upper end of the soil pipe in case the latter should be made of lead. In Fig. 6, however, this packing section is omitted and the lower face of the follower is conical for direct engagement with the conical bearing —9— of the collar —5—.

In placing the closet bowl, the collar —5— is first attached to the upper end of the soil pipe —2— and firmly secured to the floor by the screws —6— and then after placing the packing ring —8— over and upon the flange —4— of the bowl, the latter is placed

in position so as to bring the base flange —3— over and around the upper end of the collar —5— to rest upon the upper face of the floor, during which operation the bolts or studs —13— will enter their respective apertures —14— in the base flange, whereupon the blocks —15— are placed upon the bolts and the nuts —16— tightened to draw the lower marginal edge of the base flange —3— firmly against the floor and to simultaneously lock it to the collar —5— and, therefore, to the soil pipe —2— to which the collar is secured. These blocks —15— carry the adjusting screws —17— and when properly placed, said screws will be aligned with their respective bearings —8'— and will then be adjusted to press the packing ring firmly against the conical shoulder —9— with a wedging action to make a gas and liquid-tight joint, and if at any subsequent time there should be a leakage at such joint, the follower or packing ring may be additionally tightened by the same screws without in any way disturbing any of the other connections between the bowl and floor or between the bowl and soil pipe.

What I claim is:

A floor and soil pipe connection for closet bowls, said bowl having its base provided with a central annular flange co-axial with the soil pipe and a relatively larger annular flange resting upon the floor and forming with the inner annular flange an intervening chamber, a collar attached to the upper end of the soil pipe and extending into said chamber, means for securing the collar to the floor, studs secured to the collar and projecting upwardly through openings in the base of the bowl between said flanges, blocks slidably fitted on the upper ends of said studs and resting upon the base of the bowl, nuts engaging the upper ends of the studs for clamping the blocks in place and securing the base of the bowl to the floor, a packing ring wholly within said chamber between the base of the bowl and collar and provided with bearings, and adjusting screws engaged in threaded apertures in the blocks and passing through openings in the base of the bowl and engaged with the packing ring for tightening the latter.

In witness whereof I have hereunto set my hand this 4th day of September, 1915.

MICHAEL O'LEARY.
